(57) **CLAIM**

The ornamental design for an air conditioner panel, as shown and described.

DESCRIPTION

FIG. 1 is a front perspective view of an air conditioner panel; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a magnified view of the central part shown in FIG. 1; and,

FIG. 9 is a magnified view of the central part shown in FIG. 2.

Shading of the drawings is provided to indicate surface contours only and is not a claim for color, as the solid lines define the article for which ornamental design is claimed. The broken lines of FIGS. 3-7 are for the purpose of illustrating environmental structure and form no part of the claimed design.
